UNITED STATES PATENT OFFICE.

LEOPOLD DEMUTH, OF NEW YORK, N. Y.

TOBACCO-PIPE.

1,257,326.

Specification of Letters Patent. Patented Feb. 26, 1918.

Application filed July 30, 1917. Serial No. 183,498.

To all whom it may concern:

Be it known that I, LEOPOLD DEMUTH, a citizen of the United States, residing at New York, county of New York, and State 5 of New York, have invented new and useful Improvements in Tobacco-Pipes, of which the following is a specification.

This invention relates to a tobacco pipe in which the mouth piece is connected to the 10 stem of the bowl by a screw nipple made to engage a threaded socket formed in the stem.

The present invention is an improvement on my Patent No. 1,153,771, granted Sept. 15 14th, 1915, in which the threaded nipple forms an integral part of the mouth piece.

The invention is designed to provide a 20 nipple of durable construction with a short coarse thread at its front portion to engage a corresponding thread formed in the bottom of the socket to give air-tight closure to the parts.

The object of the invention is to provide a 25 nipple which can be readily disconnected from the mouth piece when broken and another substituted. This is an important item in a pipe with an expensive mouth piece such as amber or other pellucid substance, where if the nipple was broken it 30 required expensive repairs; or if of ordinary inexpensive material the mouth piece would have to be discarded.

The novel features of the invention are 35 more fully described in the following specification and claims and illustrated in the accompanying drawings in which:

Figure 1 represents a sectional side elevation of a pipe embodying this invention.

Fig. 2 is a similar view showing the 40 mouth piece detached.

Fig. 3 is a view on a larger scale of a nipple.

In this drawing the letter *a* designates a 45 bowl having a receptacle for holding tobacco. A stem *b* projects from the bowl and it has a channel *c* extending from the bottom of the receptacle. In the end of the stem is located a socket *d* having part of its depth threaded as indicated at *e*. The 50 convolutions begin at the bottom of the socket and run a short distance, the major part of the socket being unthreaded.

A mouth piece or stem *f* is preferably made 55 of horn, amber, bakelite, or hard rubber. The inner end of this mouth piece is provided with a threaded socket or bore *g* made

to engage the threaded forward portion *h* of a nipple. The nipple is preferably made of bone and it includes a projecting member *i* having a short coarse thread *j* to correspond with the thread in the stem socket. The thread begins at the front end of the nipple and extends about one-third its length. In the nipple and the mouth piece is located a channel *k* which when the nipple is screwed into the socket of the stem will register with the channel in the stem. 60

The screw stem *h* has fine threads and is slightly smaller in diameter than the projecting member *i* so as to insure a strong 70 device at the base of its junction with the mouth piece. The coarse square screw threads of the nipple with its short convolutions will not be liable to overturn and consequently bring the mouth piece out of register or line with the bowl. By reason of the short thread the mouth piece will draw up tight against the stem obviating any leakage of air or liquid between the joints. The nipple being of comparatively large 80 diameter will not split or break and the nicotin will have less effect on the coarse screw of the kind described. The parts can be easily kept in a hygienic condition by the accessibility of the screw thread for cleaning purposes. The large coarse screw also permits uniform accurate tapping or cutting thus giving perfect register and snug fit to the parts when screwed together. 85

By having the nipple threaded into the 90 socket in the stem it can be readily unscrewed when desired or when broken by anyone unskilled in the art and then interchanged.

I claim:—

1. A tobacco pipe comprising a bowl having a stem with a partly threaded socket, a detachable mouth piece, a nipple removably carried by the mouth piece, said nipple including a partly threaded portion at its 100 front end for insertion into the partly threaded socket in the stem.

2. A tobacco pipe comprising a bowl having a stem with a partly threaded socket, a detachable mouth piece provided with a 105 socket, a nipple made to engage the latter socket, said nipple including a partly threaded portion at its front end for insertion into the partly threaded socket in the stem.

3. A tobacco pipe comprising a bowl having a stem with a socket threaded a portion of its depth, the threads of which are cut 110

flush with the diameter of the unthreaded part, a detachable mouth piece provided with a threaded socket, a nipple having corresponding threads to engage the latter socket, said nipple having a portion of its length threaded to engage the socket in the stem.

4. A tobacco pipe comprising a bowl having a stem with a socket threaded a portion of its depth at the bottom, a detachable mouth piece provided with a finely threaded socket, a nipple having corresponding

threads to engage the latter socket, said nipple having a portion of its length beginning at its front end coarsely threaded to engage the socket in the stem.

In testimony whereof I have hereunto set my hand in the presence of two subscribing witnesses.

LEOPOLD DEMUTH.

Witnesses:

WILLIAM MILLER,
GRACE DE VOE.
